UNITED STATES PATENT OFFICE.

HERMAN E. LOEBE, OF JERSEY CITY, NEW JERSEY.

GAS HEATER.

Application filed October 3, 1921. Serial No. 505,005.

To all whom it may concern:

Be it known that I, HERMAN E. LOEBE, a citizen of the United States, and a resident of Jersey City, in the county of Hudson and State of New Jersey, have invented new and useful Improvements in Gas Heaters, of which the following is a full, clear, and exact description.

This invention relates to improvements in 10 gas heaters.

The usual type of gas heater, when in use, gives rise to an objectionable smell due to the incomplete combustion of the gas. This is very unsatisfactory when the heater is 15 used in apartments or rooms, and the gases escaping to cause this smell are injurious to the health of the occupants.

The object of this invention is to provide an economical gas heater provided with 20 means for causing more complete combustion than usual so as to eliminate smells and which give great efficiency in the heating power for the amount of gas consumed.

A further object is the provision of means 25 for retaining the heat so that after the gas has been discontinued the heater will continue to radiate heat.

This object is accomplished by mounting in the mantle located above the burner, a 30 flame spreader that delays the progress of the gases so as to cause good combustion, and constructing the mantle and flame spreader of a material that retains heat.

These and other objects of the invention 35 will be more clearly understood from the following detailed description and accompanying drawings.

Figure 1 is a vertical section through the heater;

40 Figure 2 is a section on the line 2—2, Figure 1;

Figure 3 is a section along the line 3—3, Figure 1;

Figure 4 shows in detail the air inlet.

45 Referring to the above-mentioned drawings, a base 10, which is of considerable weight, is provided to support the various parts of the heater. Mounted on this base is a gas inlet 11 to which gas is supplied 50 by means of a gas supply pipe 12. The upper part of the gas inlet 11 is threaded and has a coupling 13 making a threaded engagement therewith. Entering the coupling is an air inlet 14. A set screw 15 is mounted 55 in the wall of the air inlet and serves as a

means for controlling the amount of air that enters. Connected to the upper end of the coupling 13 is a tube 16 which carries a number of supporting arms 17. The upper ends of these supporting arms extend 60 radially outward and have an annular plate 18 integral therewith. Two concentric flanges 19 and 20 extend upward from the annular plate 18. A perforated casing 21 is held in position upon the annular plate 65 18 by means of the flange 19. A two-piece tubular casing made up of sections 22 and 23 is held in position on the annular plate 18 by means of the flange 20 and the screws 24 which project through the supporting arms 70 17. A cover 25 having its center portion cut away is mounted on the casing 21 and is held in position by means of the bolts 26. A perforated lid 27 is provided to close the central opening in the cover 25. An ornamental top 28 provided with a pin 29 extending vertically downward is located above the lid 27, the pin 29 engaging in an opening in the center of the perforated lid. 75

The two-piece tubular casing is made up 80 of sections 22 and 23. The annular sections, which are of greater diameter at the top than at the bottom have flanges about their lower ends that project radially inward. The upper section 23 has a shoulder 30 cut 85 around the outside of this lower end. This shoulder 30 rests upon the upper edge of the lower section and serves as a means for supporting the upper section upon the lower section. Screws 31 extend through the wall 90 of the lower section into the threaded openings provided in section 23 and serve to hold the two together. The sections of this tubular casing are preferably made of cast iron but might be made from other materials. 95

The flame spreader consists of an annular plate 32 having integral therewith an arm 33 that supports the spacing hub 34, upon the ends of which two dish-shaped plates 35 and 36 are mounted. These dish-shaped 100 plates are mounted so that they face inward. Radial grooves 37 are cut in the edge of the lower face of the plate 35. The plates 35 and 36 are greater in diameter than the opening in the center of the annular plate 32 105 but smaller in diameter than the external diameter of the annular plate. Their diameter is also less than the diameter of the sections of the mantle. The flame spreader is mounted on the flange of section 23 by 110

means of the plate 32. This flame spreader is preferably constructed of cast iron so that it will retain heat.

When the heater is in use the flame passes 5 up into the mantle and strikes the lower face of the plate 36 and is forced to the side, passing around the edges of the mantle. It then passes up through the opening in the 10 annular plate 32 and comes into contact with the lower face of the plate 35. The lower plate is shaped for spreading the flame so that it travels toward its edges. When the flame and gases come in contact 15 with the lower face of the plate 35 they escape partially through the grooves 37 and pass around the edges of the plate 35. The shape of the plate 35 causes a whirling motion of the gases and delays them sufficiently to cause complete combustion. The 20 heater and the mantle being constructed of cast iron retain a considerable amount of heat and once they have been heated the supply of gas may be cut down and the heater continues to radiate a considerable amount 25 of heat. The heater casing 21 is perforated so as to allow the heat to escape freely. A perforate lid 27 is provided in the top of the heater so that the ornamental cover may be removed and the heater used for heating 30 water or other like purposes.

I would state in conclusion that while the illustrated example constitutes a practical embodiment of my invention I do not limit myself strictly to the exact details 35 herein illustrated since manifestly the same can be considerably varied without departing from the spirit of the invention as defined in the appended claims.

Claims:

40 1. In combination with a heater a flame spreader of the class described, comprising an annular plate supported in the heater, a spacing hub extending to each side of the

annular plate and supported thereby, and two dish-shaped plates, one mounted on each 45 end of the spacing hub and both facing inward, the upper plate having grooves cut in the edge of its lower face extending radially outward.

2. In combination with a heater, a flame 50 spreader of the class described, comprising an annular plate supported in the heater, a spacing hub extending on each side of the annular plate and supported thereby, and two dish-shaped plates of greater diameter 55 than the inner diameter of the annular plate, one mounted on each end of the spacing hub and facing inward, the upper plate having grooves cut in the outer edge of its lower face, said grooves extending radially 60 outward.

3. In combination with a heater including a burner, a tubular casing mounted above the burner for enclosing the frame and a casing for enclosing the tubular casing, a 65 flame spreader of the class described, comprising an annular plate, a spacing hub supported by said annular plate, two hollow dish-shaped plates one mounted on each end of the spacing hub and facing inward, and 70 means in conjunction with the tubular casing for supporting the annular plate to support the flame spreader.

4. As a new article of manufacture, a heater of the class described, comprising a 75 burner, a heat retaining tubular casing for confining the flame of said burner carried by the latter, a casing enclosing the tubular casing, and a flame spreader including two dish-shaped heat retaining plates facing inward and spaced apart supported in the tubular casing above the burner, the upper plate having grooves cut in the edge of its lower face.

HERMAN E. LOEBE.
